UNITED STATES PATENT OFFICE.

JASPER JOHNSON, OF GENESEO, NEW YORK.

GATE.

Specification forming part of Letters Patent No. 27,367, dated March 6, 1860; Reissued January 8, 1861, No. 1,121.

To all whom it may concern:

Be it known that I, JASPER JOHNSON, of Geneseo, in the county of Livingston and State of New York, have invented a new and 5 useful Improvement in Gates; and I do hereby declare that the following is a full, clear, and exact description of the same, reference being had to the annexed drawing, forming part of this specification, in the 10 several figures of which similar characters of reference denote the same part.

Figure 1 is side view of gate showing posts and connecting therewith. Fig. 2 is a top view of same. Fig. 3 is a view showing 15 gate post and operating cords.

The nature of my invention consists in a certain combination of devices hereinafter to be set forth for opening and closing gates and securing them in such position, the 20 details of construction and operation being as follows:

In the drawing G is the gate hung between posts P P', and having across its face the guides a a'. Between which guides passes a 25 rod R, running through post P and having on its protruding end a pulley p (Fig. 3). The turning of this pulley raises and lowers the rod R between the guides a a', and by the pressure of said rod against the guides 30 in this movement causes the gate to turn

upon its hinges and open or close as the case may be. To the pulley p is permanently fastened, a cord c, branching at each extremity as seen at d d', and running through a cap C on the head of the post P. These 35 cords are carried through caps D and E on posts P'' P''' on opposite sides of the gate when closed, and have weights W pendent from their extremities. By drawing upon the elevated weight on either side the pulley 40 p is moved and the gate operated. The post P' has a catch e into which rod R falls when the gate is closed. It may be stated that this rod is bent, the branch passing through the post forming an angle with the operating portion. When open or closed the rod 45 effectually fastens the gate.

I claim—

The combination of rod R, guides a a', pulley p, and weighted cords c, with the 50 gate and posts; arranged and operating substantially as described.

In testimony whereof I have hereunto signed my name before two subscribing witnesses.

JASPER JOHNSON.
